CLAIM

The ornamental design for backpack with wings, shown and described in the attached drawings.

DESCRIPTION

FIG. 1 is a perspective view of the design for my decorative wings.

FIG. 2 is a front elevation view of the design.

FIG. 3 is a back elevation view of the design.

FIG. 4 is a right side elevation view of the design.

FIG. 5 is a left side elevation view of the design.

FIG. 6 is a top view of the design; and,

FIG. 7 is a bottom view of the design.

The broken lines showing a backpack are for the purposes of illustrating environment and form no part of the claimed design.
